UNITED STATES PATENT OFFICE.

DELAMERE B. GARDNER, OF CHICAGO, ILLINOIS.

STARTER FOR EXPLOSION-ENGINES IN SELF-PROPELLED VEHICLES.

No. 896,875.

Specification of Letters Patent.

Patented Aug. 18, 1908.

Application filed October 5, 1897. Serial No. 396,064.

To all whom it may concern:

Be it known that I, DELAMERE B. GARDNER, a citizen of the United States, residing at Chicago, in the county of Cook and State of Illinois, have invented a new and useful Improvement in Starters for Explosion-Engines in Self-Propelled Vehicles, of which the following is a specification.

My invention relates to certain new and useful improvements in starters for explosion engines in self-propelled vehicles, and is fully described and explained in the specification and shown in the accompanying drawings, in which:

15 Figure 1 is a vertical section showing the construction of my improved device, and Fig. 2 is a section in the line 2 of Fig. 1 looking in the direction of the arrow.

Referring to the drawings, A is the main engine shaft, which is rotated by the explosion engine driving the vehicle and through which the said engine can of course be rotated if desired. This shaft A carries a fly-wheel A¹, the rear face of which is provided 20 with a depression the periphery of which is conical in form to engage with a clutch B normally held in engagement with said fly-wheel by a spring b and arranged to be thrown out of such engagement by means of a 25 lever b¹ bifurcated at its lower end and provided with rollers of the usual form running in a groove in a boss provided upon the clutch member B. This portion of the construction is of course old and well known 30 and requires no particular description. The clutch member B is provided with a square central perforation in which is fitted a square shaft C capable of a limited longitudinal movement through said clutch member.

40 D is the case which contains the gears for changing the speed of the vehicle, a main gear-shaft D¹ projecting forward from the front of this case. The gear-case D is of course stationarily secured in place and is 45 provided with a boss D² concentric with respect to the shaft D¹, the said boss being provided at its forward end with an interior conical surface d. The forward end of the main gear-shaft D¹ is provided with a series of 50 screw-threads d¹ which engage with a female threaded portion at the rear of the intermediate square shaft C. A clutch member E is provided upon the rear of the intermediate square shaft C, the said member being adapted 55 to engage with the forward conical surface

of the boss D² and being controllable by means of a lever e arranged like the lever b¹.

Rigidly secured to the main gear-shaft D¹ is a member F comprising a boss f geared to said shaft, a radial web f¹ lying adjacent to the forward wall of the gear-case D, and a flange f² concentric with the shafts C and D¹. A block G is slidably mounted upon the rear end of the intermediate shaft C and between this block and the flange f² of the member F is interposed a spiral spring H.

The operation of my improved device is substantially as follows: When the engine is running to drive the vehicle the parts all occupy the positions shown in Fig. 1, and the clutch E is disengaged from the boss D². The power of the engine is transmitted from the fly-wheel to the clutch B, thence to the intermediate shaft C, and thence, through the screw-thread connection, to the main gear-shaft D¹, thus driving the vehicle. When it is desired to stop the vehicle, the clutch B is first disengaged in the usual way, thus letting the fly-wheel run free, and from that time on the intermediate shaft C and the clutch B are driven only by the momentum of the vehicle. The clutch E is then engaged with the boss D² through the medium of the lever e, thereby stopping the rotation of the intermediate shaft C and of the block G. The shaft D¹ and the member F will, however, keep on rotating and as a result the shaft C will be screwed off the shaft D¹ to a certain extent and in the meantime the spring H will be fully wound up. When the limit of winding of this spring is reached, further rotation of the shaft D¹ without the shaft C will cease, and the clutch E will necessarily slip, thus operating as a brake on the vehicle and bringing it to a stop. The parts are so proportioned and arranged that the number of turns of the shaft D¹ relative to the shaft C to reach the limit of the capacity of the spring H, will not exceed the number of turns of the screw-thread, so that the shafts will never become completely disengaged, and the threads are made of such pitch that the shaft C has ample room to perform the longitudinal movement caused by this unscrewing without contacting with the end of the main shaft A.

When it is desired to again start the vehicle, the clutch B is first engaged in the usual way and the clutch E is disengaged. The spring H then operates to rotate the inter-

mediate shaft C, clutch B, fly-wheel and engine-shaft, thus starting the engine. In the meantime the shafts C and D¹ are screwed together so that as the engine starts it drives through what amounts to a solid shaft to the change gears.

It will be obvious, of course, that while I have shown and described a starting device particularly adapted to be used between the engine and the change gear-case, it need not necessarily be located in this position, nor in fact need any change gear-case necessarily be used. The essential point is merely that the shaft A shall be a shaft, having, at least while the device is in operation, a driving connection with the explosive engine, and that the shaft D¹ shall be a driven shaft from which, either directly or indirectly, it is desired to take power.

I realize that considerable variation is possible in the details of construction without departing from the spirit of my invention, and I do not intend therefore to limit myself to the specific form herein shown and described.

What I claim as new, and desire to secure by Letters Patent, is:

1. The combination with a driving shaft having operative connection with an internal-combustion engine and a driven shaft adapted to be connected to and disconnected from said driving-shaft, of means for absorbing the momentum of said driven shaft and the parts connected therewith and storing the energy thereof while the driven shaft is disconnected from the engine, and means for transmitting such stored energy to said driving shaft to start the engine.

2. The combination with a driving shaft having operative connection with an internal-combustion engine and a driven shaft, of means for connecting said shafts whereby the normal operation of the driving shaft will drive the driven shaft and the parts connected thereto, means for disconnecting said shafts, means for absorbing and storing the energy of the momentum of the driven shaft and the parts operated thereby while said shafts are disconnected, and means for transmitting such stored energy to the driving shaft to start the engine connected therewith.

3. The combination with a driving shaft having connection with an internal-combustion engine and a driven shaft, of means adapted to connect said shafts and to disconnect the same, a spring adapted to absorb the momentum of the driven shaft and the parts carried thereby while said shafts are disconnected, and means for connecting said spring with said driven shaft to rotate the same for the purpose of starting said engine.

4. The combination with a driving shaft connected to an internal-combustion engine and a driven shaft, of an elastic member nor-

mally movable with said shaft, means for connecting said shafts together whereby one drives the other, permanent means of connection between one of two relatively movable points upon said elastic member, by whose relative movement power is stored up or given off, means for locking the other said relatively movable point in a stationary position whereby the momentum of the driven shaft is absorbed in the elastic member, and means for connecting said point to the driving shaft to set the same in motion when the driven shaft is stationary.

5. The combination with a driving shaft connected to an internal-combustion engine and a driven shaft, of means of connection between said shafts whereby one drives the other, and means for disconnecting said shafts, a spring having one end connected to the driven shaft, and means for alternatively connecting the opposite end of said spring to a stationary point or to the driving shaft, whereby power may be stored in the spring by absorbing momentum of the driven shaft and subsequently transmitted to the driving shaft for starting the engine.

6. The combination with a driving shaft connected to an internal-combustion engine and a driven shaft, of means for connecting the shafts whereby one drives the other, a spring connected at one end to the driven shaft, means for connecting the other end of the spring frictionally with a stationary point whereby the momentum of the driven shaft and parts carried thereby can be absorbed in the spring until a certain tension is obtained, after which slippage will take place, and means for at will disconnecting said end of the spring from said stationary point and connecting the same to the driving shaft for starting the engine connected thereto.

7. The combination with a driving shaft having an internal-combustion engine connected thereto and a driven shaft, of an intermediate shaft connected to the driven shaft and capable of a limited rotation with respect thereto in either direction, a clutch whereby the intermediate shaft can be connected to the driving shaft, a spring interposed between the driven shaft and the intermediate shaft, said spring being at its point of lowest normal tension when the shafts are at one limit of relative rotation, and a second clutch whereby the intermediate shaft can be frictionally locked in a stationary position, whereby, by disengaging the intermediate shaft from the driving shaft and locking it stationary, the momentum of the driven shaft and the parts connected thereto can be stored in the spring and subsequently transmitted to the driving shaft by connecting the intermediate shaft therewith and releasing the same from its stationary position, the intermediate shaft and driving

shaft moving relatively during the action of said spring.

8. In a device of the class described, the combination with a main shaft connected to 5 an internal-combustion engine, of an intermediate shaft and a driven shaft having a screw-thread connection with said intermediate shaft, a clutch by means of which the intermediate shaft can be secured to the 10 driving shaft, a clutch whereby the intermediate shaft can be locked stationary, and a spring interposed between the driven shaft and the intermediate shaft.

9. The combination with a driving shaft 15 connected to an internal-combustion engine,

a driven shaft and an intermediate shaft having a threaded connection with the driven shaft, of clutches whereby the intermediate shaft can alternatively be locked to the driving shaft or to a stationary device, a flanged 20 member secured to the driven shaft and overhanging the intermediate shaft, a block slidable upon the intermediate shaft and within said flanged member, and a spring interposed between said block and said flanged 25 member.

DELAMERE B. GARDNER.
